UNITED STATES PATENT OFFICE

162,297

SELF-CONTAINED AIR CONDITIONING UNIT

Lurelle Guild, New York, N. Y., assignor to Carrier Corporation, Syracuse, N. Y., a corporation of Delaware

Application August 7, 1950, Serial No. 11,657

Term of patent 7 years

(Cl. D62—4)

To all whom it may concern:

Be it known that I, Lurelle Guild, a citizen of the United States, residing at New York, State of New York, have invented a new, original, and ornamental Design for Self-Contained Air Conditioning Unit, of which the following is a specification, reference being had to the accompanying drawing, forming a part hereof.

The figure is a front perspective view of a self-contained air conditioning unit showing my new design. The side not illustrated is the same as that illustrated.

I claim:

The ornamental design for a self-contained air conditioning unit as shown and described.

LURELLE GUILD.
